OXYGEN INHALATOR

Lothar Miczka, 4370 La Salle Strasse 13, Post Foch 43,
Marl, Westphalia, Germany

Filed Oct 28, 1968, Ser. No. 14,190

Claims priority, application Canada Apr. 29, 1968

Term of patent 14 years

Int. Cl. D24—02

U.S. Cl. D83—1

FIG. 1

FIG. 2

FIG. 3

FIG. 1 is a perspective view of an oxygen inhalator, with the cover member disengaged from the body portion, showing my new design;

FIG. 2 is a side elevation thereof; and

FIG. 3 is a top plan view looking in the direction of line 3—3 of FIG. 2.

The end portion as seen from the left of FIG. 1 is plane.

I claim:

The ornamental design for an oxygen inhalator, as shown and described.
